UNITED STATES PATENT OFFICE.

JAMES R. FERGUSON AND JOHN FERGUSON, OF CHESTER, CONNECTICUT.

SLEEVE-HOLDER.

SPECIFICATION forming part of Letters Patent No. 391,307, dated October 16, 1888.

Application filed December 24, 1887. Serial No. 258,881. (No model.)

To all whom it may concern:

Be it known that we, JAMES R. FERGUSON and JOHN FERGUSON, citizens of the United States, residing at Chester, in the county of Middlesex and State of Connecticut, have invented certain new and useful Improvements in Sleeve-Holders; and we do hereby declare that the following is a full, clear, and exact description of the same, reference being had to the annexed drawings, making a part of this specification, and to the letters and figures of reference marked thereon.

Figure 1 of the drawings is a perspective view of our improved sleeve-holder, and Fig. 2 a detail perspective view showing a modification of one of the jaws.

The present invention has relation to that class of sleeve-holders constructed of wire, which are provided with gripping-jaws at one end and loops or rings at the other, through which the thumb or finger is inserted after the jaws grip the sleeve, thereby holding the sleeve down and in place while putting on the outer garment.

Heretofore the above class of devices was usually formed of two sections or pieces of wire, which were hinged or pivoted together near their gripping ends. This constructing the device of two lengths of wire and afterward pivoting them together is a feature that the present invention is designed to avoid, thereby enabling the holder to be manufactured at a less cost, and, there being no pivoting of the parts and no rivets used, there is less danger of the device getting out of order.

To attain this object is the purpose of the invention; and it consists in forming the holder of a single piece of wire, substantially as shown in the drawings, and hereinafter described and claimed.

In the accompanying drawings the holder, as therein illustrated, is constructed of a single length of spring-wire, bent so as to form the arms A and ring or loop B, which is disposed at an obtuse angle to the arms and is of the required size to conveniently insert the thumb or finger through it. These arms are of any preferred length, and at their extremi-

ties are bent inwardly, as shown at a, and thence terminate in jaws C for the purpose of 50 gripping the sleeve of the garment.

It is essential in this class of sleeve-holders that the ring B be disposed at an obtuse angle with the arms A, so that, after the gripping-jaws are made to engage the sleeve, said ring 55 will be in a position to conveniently insert the thumb or finger through it, which would be difficult were the ring on the same plane with the arms. It is also of importance that the extremities of the arms A have inward bends to a, so that when the slide b is down to compress them the gripping-jaws will be brought closely together upon the garment. These jaws may be formed by bending the wire of the arms into rings, as shown in Fig. 1, or disks 65 or other forms of heads may be used, as shown in Fig. 2, which are constructed of wood, rubber, cork, or other suitable material and connected to the extremities of the arms in any well-known manner. The jaws are closed upon 70 the sleeve of the garment by means of the slide b, and when the slide is forced up in the direction of the loop or ring the springy quality of the wire will force the jaws apart, as shown in full lines, Fig. 2, the broken lines 75 showing the jaws compressed and the slide pushed down.

Having now fully described our invention, what we claim as new, and desire to secure by Letters Patent, is—

The sleeve-holder herein described, formed of a single piece of wire bent to form a pair of arms having a loop or ring at one end which is disposed at an obtuse angle to the plane of the arms, and the opposite end of the arms 85 having inward bends terminating in gripping-jaws, and a slide to close or open said jaws, as and for the purpose set forth.

In testimony that we claim the above, we have hereunto subscribed our names in the 90 presence of two witnesses.

JAMES R. FERGUSON.
JOHN FERGUSON.
